United States Patent Office

Des. 213,939
Patented Apr. 22, 1969

213,939

CHAIN SAW

Wilford B. Burkett, Pacific Palisades, Anthony J. Carsello,
Palos Verdes Peninsula, and Harry I. Hazzard, Los
Angeles, Calif., assignors to McCulloch Corporation,
Los Angeles, Calif., a corporation of Wisconsin

Filed Apr. 2, 1968, Ser. No. 11,260

Term of patent 14 years

Int. Cl. D8—02

U.S. Cl. D93—3

Fig. 4

Fig. 5

FIG. 1

FIG. 1 is a perspective view of a chain saw;
FIG. 2 is a left side elevation view;
FIG. 3 is a right side elevation view;
FIG. 4 is a top plan view;
FIG. 5 is a rear elevation view;
FIG. 6 is a front elevation view; and
FIG. 7 is a bottom view.
The dominant features of our design reside in the
portions shown in full lines.

We claim:

The ornamental design for a chain saw, substantially
as shown and described.
